UNITED STATES PATENT OFFICE.

FRITZ FISSLTHALER, OF SALZBURG, AUSTRIA-HUNGARY.

CONVEYER.

1,022,359.

Specification of Letters Patent.

Patented Apr. 2, 1912.

Application filed April 1, 1911. Serial No. 618,270.

To all whom it may concern:

Be it known that I, FRITZ FISSLTHALER, a subject of the Emperor of Austria-Hungary, residing at Salzburg, in the Empire of Austria-Hungary, have invented a new and useful Conveyer, of which the following is a specification.

My invention consists of a conveyer or the like produced in a novel manner from 10 metallic sheets.

The sheets are first so bent in two lines parallel to their long edges, that the two side portions projecting to the same side are approximately at right angles to the 15 central body, and the two side portions are divided by parallel cuts into juxtaposed strips. The bodies of the several sheets are then twisted to form a tube, so that their strips form helical curves. Preferably in 20 the helical curve the free ends of the strips of the sheet in any turn of the conveyer or the like are made to alternate with the free ends of the strips of the sheet in any neighboring turn and the free ends of all the 25 strips are so bent as to form eyes, through which a wire can be passed for connecting the strips together. The bodies of the several sheets forming parts of the conveyer may be connected with one another at their 30 ends in any known manner, say by screws and nuts or by rivets in lap-or butt-joints, or by welding.

I will now proceed to describe my invention with reference to the accompanying 35 drawing, in which—

Figure 1 is a perspective view of a part of a conveyer or the like constructed according to my invention, Fig. 2 is an end view of the same, Fig. 3 is a development of 40 a part of the conveyer, and Fig. 4 is a cross section through this part, after the two series of strips have been bent upward.

Similar letters of reference refer to similar parts throughout the several views.

45 A conveyer or the like shown at Figs. 1 and 2 can be formed from a number of preferably long rectangular, parallelogrammatic or trapezoid metallic sheets in the following manner. Each sheet is along its two longitudinal edges divided by parallel cuts into two series of juxtaposed strips *b b* and *c c*, so that a central body *a* is left uncut, as is

clearly shown at Fig. 3. Then the sheet is bent in two parallel lines, so as to bend the two series of strips *b b* and *c c* upward, 55 about at right angles to the body *a*, as is shown at Fig. 4. Where so preferred, of course the sheet may be first bent in the said two parallel lines, before the two erect side portions of the sheet in Fig. 4 are cut 60 up into two series of strips. Preferably before bending the sheet in the said two parallel lines the free ends of the strips *b* and *c* in each series are so bent as to form eyes, as is shown at Fig. 1, so that a wire *d* can 65 be passed through them. Now the body *a* of each sheet is in any known manner so twisted as to form a tube. Then the two series of strips *b b* and *c c* of the sheet are spread and form two combs. If the sheet is 70 sufficiently long, its body *a* may form one turn or more than one turn, perhaps several turns of the tube representing the central part of the conveyer shown at Figs. 1 and 2. It is essential, that the edges of the 75 body *a* in any turn come in contact with the edges of the body in the next following turn and that the free ends of the upper strips *c c* of the original sheet in any turn of the conveyer engage between the free 80 ends of the lower strips *b b* of the sheet in the next following turn, so that a wire *d* can be passed through the eyes at these free ends for connecting together the strips of the two series in the same helical curve (see 85 Fig. 2). The bodies *a a* of the several sheets forming parts of the conveyer or the like may be connected together at their ends in any known manner, for example by means of screws and nuts or rivets in lap-or butt- 90 joints, or by welding with the aid of an oxyhydrogen-blowpipe or the like.

The structure shown and described may be made from other materials than metallic sheets, in which case the bodies of the several sheets may be connected together in any known manner, for example by gluing or the like.

I claim:

1. A conveyer comprising a single integral strip of sheet like material having an intact central body portion spirally disposed to form a tubular supporting body, the margins of said strip being bent and having

their edges connected and forming a spiral conveying portion.

2. A conveyer comprising a single strip of sheet like material having an intact body portion spirally disposed to form a tubular body, the margins of said strip being bent radially and having their outer

edges connected and forming a spiral conveying portion.

FRITZ FISSLTHALER.
